UNITED STATES PATENT OFFICE.

CHARLES W. HINCHCLIFFE, OF LAWRENCE, MASSACHUSETTS.

WINDOW-SCREEN.

1,257,707.

Specification of Letters Patent. Patented Feb. 26, 1918.

Application filed August 24, 1917. Serial No. 187,934.

To all whom it may concern:

Be it known that I, CHARLES W. HINCHCLIFFE, a citizen of the United States, residing at Lawrence, county of Essex, State of 5 Massachusetts, have invented an Improvement in Window-Screens, of which the following description, in connection with the accompanying drawing, is a specification, like characters on the drawing representing 10 like parts.

This invention relates to window screens of a type adapted to be slidably positioned in a window frame.

In screens of this type the runners on the 15 window frame usually extend only half-way up and, to insert and remove a screen, the screen must be lifted until its channels are free from the runners. In this novel structure, there is provided a screen adapted to 20 be used with runners which extend the vertical length of the window and is so constructed that the screen may be removed at any point.

The principal object of this invention is 25 to provide a screen which may be readily inserted and removed at any point along the vertical length of the window frame.

Other objects of the invention will more 30 fully appear from the following description and the accompanying drawings and will be pointed out in the annexed claims.

In the accompanying drawings there has been disclosed a structure designed to carry out the objects of the invention, but it is to 35 be understood that the invention is not to be confined to the exact features shown as various changes may be made within its reasonable scope.

In the drawings:

40 Figure 1 is a view in elevation of the outside of the screen as inserted in the window frame;

Fig. 2 is an enlarged, broken-out view of the screen on the line 2—2 of Fig. 1;

45 Fig. 3 is an enlarged view of the upper portion of the screen broken away.

The window frame 1 is of the usual construction and has applied thereto a pair of runners 2 which preferably extend the vertical 50 length of the window frame and along which the screen is adapted to slide. These runners are desirably formed of thin strips of angle iron and are secured to the inside of the window frame. In this selected embodiment, the screen is provided with a main wooden frame 3 which carries the wire net-

ting 4. This netting is preferably stretched across the screen frame 3 and the perimetrical portions of the netting are secured to the frame by means of an auxiliary frame. 60 This auxiliary frame also functions to reinforce the window frame of the screen. It consists of uprights 5 and 6 and the top and bottom bars 7 and 8. These uprights and bars are preferably formed of thin 65 metallic strips and are screwed to the sides and top and bottom, respectively, of the screen frame, the edge portions of the netting being held between the four metallic strips and the four members composing the 70 wooden frame. The sides of the screen frame are positioned against the two outdoor faces of the runners. Each of these vertical frame sides is preferably cut away or planed down to an amount substantially 75 equal to the thickness of a runner. Therefore, when the surfaces of the cut away portions are sealed against the outer faces of the runners, a guiding or channel-forming means may be secured to the frame and 80 overlie these cutaway portions and engage the inner faces of the runners. The metallic upright 5 extends to the vertical edge of the wooden frame and thereby forms a vertical channel 9 in conjunction with the cutaway 85 portion of the frame side which it overlies. This channel is adapted to receive one of the runners 2 of the wooden frame. The runner 2 has only such play therein as will 90 permit the screen freely to be moved up and down. The other side of the screen is provided with a means movable on the frame to form guides normally to hold the frame on the runners but which can be moved out of position to permit the demounting of the 95 screen. The metallic upright 6 on the opposite side of the screen frame is narrower than the upright 5. This narrower upright 6 extends only to the vertical cutaway portion of the wooden screen frame at this side and 100 does not overlie the same so that a channel is not formed at this side of the screen. The runner 2 at this side is held slidably adjacent the cutaway portion of the screen by means of the novel movable guiding 105 means.

This guiding means which engages the runners in coöperation with the cutaway portion of the upright 6 comprises preferably two members, one each at the top and 110 bottom of the window screen. They are similar and but one is necessary to be de-

scribed. Each consists of a guide 10 which is pivotally mounted to the screen frame and is adapted to extend over the cutaway portion of the screen frame. Sufficient space is left between the guide and the cutaway portion of the screen to permit the reception of the runner of the window frame therebetween.

This guide 10 may be formed of a narrow thin piece of sheet metal and pivotally secured at one end as at 18 to the screen frame. It is mounted so that, when moved to normal guiding position, its flat face is presented in a plane substantially parallel to that of the runner. The upper and lower guides thus function to hold the screen frame in slidable position on the runners. While both sides may be provided with the novel guiding means, it is preferable to provide a permanent channel on one side of the screen as the provision of the guides on one side is sufficient to permit the facile demounting or removal of the screen. When it is desired to remove the screen from the window frame, the two guides are swung about their pivots 18 until they are clear of the runners when the screen is released and may be pulled sidewise to remove the vertical channel from the other runner of the window frame.

Means for locking the guide in normal runner-engaging position are also provided. This is effected by a locking member pivotally movable mounted on the screen frame and adapted to engage a guide 10 when the latter is in normal operative position. These locking members are similar and one is provided to lock each guide. Each guide is preferably provided with a flange 11 which, when the guide is in normal position, is horizontally seated upon the upper surface of the top of the screen frame and, in case of the lower guide, is similarly seated against the lower surface of the bottom of the screen frame. The locking member 12 in this selected embodiment, is made of a narrow piece of sheet metal and is pivotally mounted at 19 on the screen at one end to swing in a path substantially at a right angle to the path of movement of the guide 10. When the guide is moved to operative position, the locking member 12 may be moved to rest upon the flange 11 of the guide and hold it against movement about its pivot 18. The guide 10 and the locking member 12 are preferably made of pieces of small angle iron which thus provides the guide 10 with an integral flange 11. The flange is cut away at the end opposite the pivot in order to leave a thin tongue to engage the runner, while the flange remains on the major portion of the guide in order to afford a detent surface for the pivoted locking member. The upstanding flange 13 of the locking member 12 offers a convenient medium for manipulating this device. Preferably, the

top and bottom metallic strips 7 and 8 of the auxiliary frame of the screen extend above and below the corresponding members of the wooden screen frame and to these projecting portions are secured the upper and lower pivoted guides so that the guides may swing in a substantially vertical plane while the locking members 12 are secured to the respective end faces of the screen frame and can therefore pivot in a substantially horizontal plane.

A simple means of holding the screen in uppermost position is afforded by means of a plurality of holes 14. Through any one of these holes may be projected a pin or nail 80 to be received in a hole 15 in the upper portion of the window frame. Similarly opposed pairs of holes 16 are provided in the runners within which may be inserted a similar device to permit the bottom of the 85 screen frame to rest upon the projecting portion and thus to hold the screen in a plurality of elevated positions. In this embodiment, the hole 15 is formed in a strip 17 of angle iron, one angular portion of which 90 is secured to the under face of the cross-bar forming the top of the usual wooden window frame. When the screen is in uppermost position, the other depending portion of the strip 17 functions to provide an insect-tight 95 closure at this portion of the window frame. As shown in Fig. 1, the strip 17 is set inwardly from the plane of the two runners 2. Thus, in uppermost position of the 100 screen frame, the top strip 7 of the screen frame and the guide 10 will be positioned against or closely adjacent this window frame strip 17 and form therewith an insect-tight closure even when the window frame is warped or distorted in construction or in 105 service.

By the employment of this novel structure, the screen may be readily inserted and removed and, furthermore, it may be so manipulated at any vertical position with relation to the window frame. This is a great convenience over the usual type in which the runners extend only part way on the window frame and the screen structure must be moved vertically until the usual channels on 115 each side of the screen are free from the runners.

Having thus described my invention, what I claim as new and desire to secure by Letters Patent is:

1. A window screen having a netting and a frame carrying the netting and adapted to be slidably mounted on runners in a window frame, means movable on said screen frame to form guides normally to hold the frame 125 on the runners, a member on said screen frame to lock the guiding means in normal position whereby when unlocked the guide may be swung out of position and the screen demounted.

2. A window screen having a netting and a frame carrying the netting and adapted to be slidably mounted on runners in a window frame, the screen frame having means on one side to receive a runner and the other side of the frame having a surface adapted to slide over one face of the other runner, guides movably mounted on the screen frame at its top and bottom and adapted to be moved to engage the last mentioned runner on its face opposite the face engaged by said surfaces of the screen frame.

3. A window screen having a netting and a frame carrying the netting and adapted to be slidably mounted on runners in a window frame, the screen frame having means on one side to receive a runner, a guide pivotally mounted on both the top and bottom of the screen frame on the side opposite said means, each of said guides being adapted to pivot in a plane parallel to that of the adjacent runner, and a locking member pivoted adjacent each guide and movable only in a plane at an angle to the path of the guide whereby the locking member may be positioned over a portion of the guide when in operative position and movement of the guide prevented.

4. A window screen having a netting and

a frame carrying the netting and adapted to be slidably mounted on runners in a window frame, the screen frame having a channel at one side to receive a runner, a guide pivotally mounted on both the top and bottom of the screen frame on the side opposite said channel, each of said guides being adapted to pivot in a plane parallel to that of the adjacent runner, an integral flange on each guide, and a locking member pivoted adjacent each guide and movable only in a plane at an angle to the path of the guide whereby, when the guide is in normal operative position, the locking member may be positioned over the flange of the guide and movement of the guide prevented.

5. A window frame, a transverse strip depending from the top transverse portion of the frame, a screen having a netting and a frame carrying the netting and adapted to be slidably mounted on runners in the window-frame, and means for holding the screen in uppermost position whereby the depending strip forms an insect-tight closure in conjunction with the screen frame.

In testimony whereof, I have signed my name to this specification.

CHARLES W. HINCHCLIFFE.
